UNITED STATES PATENT OFFICE.

JOSEPH D. LACROIX, OF BALTIMORE, MARYLAND, ASSIGNOR, BY MESNE ASSIGNMENTS, TO THE ANGLO-AMERICAN PATENT BOTTLE COMPANY LIMITED, OF LONDON, ENGLAND.

NON-REFILLABLE BOTTLE.

1,167,413.

Specification of Letters Patent.

Patented Jan. 11, 1916.

Application filed January 20, 1912. Serial No. 672,428.

To all whom it may concern:

Be it known that I, JOSEPH D. LACROIX, a citizen of the United States, residing at Baltimore city, State of Maryland, have invented certain new and useful Improvements in Non-Refillable Bottles, fully described and represented in the following specification and the accompanying drawings, forming a part of the same.

10 This invention relates to improvements in non-refillable bottles.

It is the primary object of the present invention to simplify the construction and thereby cheapen the cost of the valve and 15 baffle mechanisms of such bottles.

To this end the invention consists of a valve which not only acts as such but because of its construction provides the weight necessary for its proper operation, thus doing away with a separate weight, and also provides so-called baffle mechanism for preventing engagement of the valve by means of valve tampering instruments, such as a piece of wire, thus doing away with one of 25 the baffle members necessarily present in non-refillable bottles.

Another object of the invention is to provide a valve which is more sensitive in its operation than prior valves, whereby, in the 30 tilting of the bottle to pouring position, a quicker or earlier opening movement of the valve is secured than in prior constructions.

In the accompanying drawing Figure 1 is a vertical elevation of a bottle neck of the 35 non-refillable type equipped with the present invention in its preferred form; Fig. 2 is a similar view of the bottle neck inverted to pouring position; Fig. 3 is a bottom plan view of the bottle neck removed from or before its attachment to the bottle body, with 40 the valve and valve seat removed so as to show the internal construction of the bottle neck; and Fig. 4 is a view similar to Fig. 1 illustrating a modification hereafter described.

Referring to said drawing, 1 represents the bottle neck and 2 an auxiliary bottle neck secured thereto by a band 3 of metal spun over a shoulder 4 of the auxiliary neck 50 2 and into recesses 5 on the neck 1. The auxiliary neck 2 is formed preferably of porcelain, with a depending annular and substantially centrally disposed obstruction or disk 6 constituting, with contiguous parts 55 of the bottle neck, a stationary baffle mech-

anism coacting with a baffle member carried by the valve, as presently described. The disk 6 is connected with the neck 2 by vertical arms 7 suitably spaced to permit the passage of liquid from the bottle between them and disk 6. Below the baffle member 6 the auxiliary neck is provided with a valve chamber generally of truncated cone shape and provided with vertical ribs 8 suitably spaced to provide for the passage of liquid between them and past the disk 6. This valve chamber has also ribs or steps 9 formed therein so that the interior of the valve chamber will conform approximately to the shape of the valve 10. This valve 10 is also generally of truncated cone shape and of a diameter, at its base, slightly greater than the diameter of the opening in the valve seat 11, and slightly less than the inner diameter of the valve chamber at its base, so as to provide for a slight movement of the valve laterally without, however, uncovering the opening in the valve. The valve seat 11 is in the form of a ring having a flange resting upon the upper end of the neck 1 and also in a suitable recess 12 formed in the lower end of the auxiliary neck 2. The valve 10 rests thereon with the minimum amount of contact therewith so that it may freely tilt with relation thereto in its opening and closing movements. It may be noted here that between the abutting ends of the necks 1 and 2 is preferably interposed an annular packing of suitable material to prevent leakage and that the flange of the valve ring 11 rests upon such packing ring.

The valve 10 is preferably made of porcelain and of such dimensions that the valve will provide the weight necessary to seat it, thus doing away with the use of a separate valve-weight. Furthermore, the valve 10 and the stationary baffle mechanism, of which disk 6 forms part, are so arranged relatively to each other as to be in close proximity, so that the upper end of the valve provides a baffle member which, coacting with said stationary baffle mechanism, will prevent tampering with the valve, to unseat it, by means of a wire or other device. Further protection against tampering with the valve is provided by the construction of the valve in other particulars, namely, in the provision, midway of the length or height of the valve, of a circular

groove or recess 13 which would receive the end of the wire or other instrument and thus arrest its further movement, if it should happen to pass the disk 6 and the upper end of the valve.

The valve 10 of Figs. 1-3 is so proportioned as to size and shape, and the adjacent face of the valve chamber is so shaped or inclined, that the valve in opening and closing will tilt on a point midway of its length; in other words, at the upper edge of the flange forming the groove or recess 13. The adjacent wall of the valve chamber is, as will be observed, not parallel with the sides of the valve, but diverges downwardly, so as to provide room for free tilting movement of the valve without any sliding contact with the side surfaces of the latter, the only part of the valve contacting with the valve chamber wall, or rather the vertical ribs thereof, being, as before stated, that in line with the upper edge of the flange forming the groove or recess 13. A valve thus balanced and tilting at a point midway of its length has been found to be much more sensitive and, therefore, quicker in its opening and closing movements than one in which the tilting takes place at the end of the valve.

In the construction shown in Fig. 4, the valve 10 is provided at its upper end with a recess 14 for receiving and arresting the further movement of any wire or other valve tampering device that may be introduced between the valve and baffle 6. In this case the ribs 8 are substantially parallel to the vertical walls of the valve 10 but the latter, as indicated at 15, has a circumferential depression because of which and of the size and shape of the valve the latter in its opening movements will tilt upon the vertical ribs 8 at a point just above such depression 15.

What is claimed is—

1. In a non-refillable bottle, the combination of a neck portion having a conoidal valve chamber, a separable valve seat device having an opening and a flat valve-seating surface around said opening, said valve seat device being arranged at the bottom of the valve chamber, and a pyramidal valve device having its base provided with a flat portion arranged to coact with the flat

valve-seating surface of the valve seat, and having a fulcrum portion intermediate its base and top arranged to be brought into engagement with the wall of the valve chamber when the bottle is tipped, whereby the valve device will tilt on said fulcrum portion to open the valve.

2. In a non-refillable bottle, the combination of a neck portion having a conoidal valve chamber, a separable valve seat device having an opening and a flat valve-seating surface around said opening, said valve seat device being arranged at the bottom of the valve chamber, a pyramidal valve device having its base provided with a flat portion arranged to coact with the flat valve-seating surface of the valve seat, and having a fulcrum portion intermediate its base and top arranged to be brought into engagement with the wall of the valve chamber when the bottle is tipped, whereby the valve device will tilt on said fulcrum portion to open the valve, and a baffle device secured within the neck portion above the valve device and arranged to limit the movement of the latter.

3. In a non-refillable bottle, the combination of a neck portion having a conoidal valve chamber, a separable valve seat device having an opening and a flat valve-seating surface around said opening, said valve seat device being arranged at the bottom of the valve chamber, a pyramidal valve device having its base provided with a flat portion arranged to coact with the flat valve-seating surface of the valve seat, the valve device also having a portion provided with a peripheral surface arranged to act as a fulcrum in tilting the valve, and with an interior downward sloping surface arranged to serve as a baffle surface, and a baffle device secured within the neck portion above the valve device and arranged to limit the movement of the valve and coact with the baffle surface of the valve device to prevent tampering with the valve.

In testimony whereof, I have hereunto set my hand, in the presence of two subscribing witnesses.

JOSEPH D. LACROIX
